UNITED STATES PATENT OFFICE

GRANVILLE A. HUMASON, OF HOUSTON, TEXAS, ASSIGNOR OF ONE-HALF TO
J. A. LOGAN

CASING HEAD

Application filed December 11, 1928. Serial No. 325,294.

This invention relates to new and useful improvements in a casing head.

One object of the invention is to provide a casing head adapted to be secured to the upper end of casing in a well bore and formed to provide an anchorage for the pump tubing in said casing as well as to form a fluid tight seal between the tubing and casing.

Another object of the invention is to provide, in a casing head, a novel type of tubing slip, or tubing holder which is formed to wedge around the pump tubing to grip and anchor said tubing against movement in the casing and to form a fluid tight joint between the tubing and casing, as well.

A further feature of the invention resides in the provision of a novel type of tubing slip, having detachable means for handling the same.

With the above and other objects in view this invention has particular relation to certain novel features of construction, operation and arrangement of parts an example of which is given in this specification and illustrated in the accompanying drawings wherein:—

Figure 1 shows a side elevation of the casing head, partly in section.

Figure 2 shows a fragmentary vertical sectional view of a modified form thereof.

Figure 3 shows a horizontal sectional view of the tubing slip employed.

Figure 4 shows a side elevation thereof.

Figure 5 shows a side elevation of the device partly in section, showing a modified form of tubing slip employed.

Figure 6 shows a fragmentary vertical sectional view of said modified form of slip.

Figure 7 shows an upper end view of said form of slip.

Figure 8 shows a cross sectional view thereof.

Figure 9 shows a side elevation thereof, and

Figure 10 shows a cross sectional view thereof, taken on the line 10—10 of Figure 9.

Referring now more particularly to the drawings, wherein like numerals of reference designate similar parts in each of the figures the numeral 1 designates a casing set

in a well bore and the numeral 2 designates the tubular body of the casing head which is connected to the upper end of the casing by the coupling 3, and which has the lateral branches, or flow lines, 4, 4. The upper end of the body has an upwardly flared internal seat 5 and the external right hand threads 6. There is a tubular nipple 7 whose lower end has the internal downwardly flared seat 8 and the external left hand threads 9 and the nipple is connected to the upper end of the body by the coupling 10. The nipple has an internal annular shoulder 11 on which the packing 12 is seated which is held in position by the gland 13. This gland is held against the packing by means of a flange nut 14 which engages the outer end of the gland and is screwed onto the upper end of said nipple 7. The packing 12 forms a fluid tight joint between the nipple 7 and the pump tubing 15.

There is a tubing slip formed of the jaws 16. These jaws are hinged together except at one side of the slip, and the lower and upper ends of the slip are tapered to conform to the contour of and fit within the respective seats 5 and 8. At the open side of the slip there are the handles 17, 17, screwed into the free ends of the corresponding jaws and by means of which the slip may be handled. The inner surfaces of the jaws are toothed, the teeth at the lower ends being upwardly inclined to engage the tubing and hold it against downward movement, and the teeth at the upper ends of the jaws are downwardly pitched so as to engage and hold the tubing against upward movement.

In the form shown in Figure 2, a packing ring, as 18, may be inserted between the adjacent ends of the body 2' and nipple 7' said ring being formed of suitable packing material and being provided with seats which are formed to fit closely against the corresponding ends of the tubing slip.

In the form shown in Figure 5 the upper ends of the slip jaws 16' are provided with suitable packing 19 which closely surrounds the tubing 15 and forms a tight joint therewith so that the packing 12, the gland 13 and the clamp nut 14, shown in Figure 1 may be

dispensed with in this form. The coupling 10 may be provided with suitable handles or grips 20, by means of which the coupling may be turned.

5. In each form the slip may be tightened into clamping relation about the tubing 15 by turning the coupling 10 to the right.

In assembling the device when the tubing has been lowered to the desired point in the 10 casing the handles 17 may be screwed into the sockets provided for them in the slip and the slip then seated in the flared seat at the upper end of the body around the tubing, and the handles then unscrewed and removed. 15 The coupling 10 may then be screwed onto the upper end of the body, 2, or 2', as the case may be, and the nipple with the associated packing 12, if the packing be necessary, then assembled in position and the coupling 20 then appropriately turned to tighten the slips against the tubing.

The forms shown are for the purposes of illustration and changes in design and mechanical construction may be made and equivalents substituted for the parts shown within 25 the principle of the invention.

What I claim is:—

1. A casing head including a coupling tubular members whose adjacent ends are 30 connected by said coupling said connected ends being formed each with an internal flared seat, a tubing slip whose ends are tapered and seated in said respective seats said slip being adapted to engage and support a tubing suspended in a well and including an annular packing between said tubing and one of said couplings.

2. A head for a well casing including a coupling, tubular members whose adjacent ends each have an internal flared seat and are connected to the coupling by right and left hand threads, respectively, and are spaced apart, a tubing slip whose ends are tapered and seated in said respective seats, said slips being formed of sections, hinges connecting said sections and arranged between said tubular members.

3. A head for a well casing including a coupling, tubular members whose adjacent ends are connected by said coupling, said connected ends being formed each with an internal flared seat, a tubing slip whose ends are tapered and seated throughout their tapered areas in said respective seats, said slip being formed of jaws hinged together, and being open at one side.

4. A head for a well casing including tubular members whose confronting ends are spaced apart and provided each with an internal seat, a coupling connecting said members by means of right and left hand threads, respectively, a tubing holder formed of jaws and whose ends are seated in said respective seats, hinges connecting said jaws and located 35 in the space between said tubular members.

5. A head for a well casing including two tubular members, a tubular coupling connecting said members, a tubing holder arranged within said coupling, said members being provided with confronting flared seats, and 70 the ends of said holder being tapered and fitted throughout their tapered areas into the respective seats.

6. A casing including two tubular members, a tubular coupling connecting said members, a tubing holder arranged within said coupling, said members being provided with confronting flared seats, and the ends of said holder being tapered and fitted into the respective seats, means in the holder for engaging a tubing therein to prevent the upward or downward movement of the tubing and annular packing means incorporated into said holder and forming a fluid tight joint between the tubing and one of the coupling 80 members.

7. A casing head including a tubular body whose upper end is upwardly flared forming an internal flared seat, a tubular nipple whose lower end is downwardly flared forming an internal flared seat, a tubular coupling threaded onto the upper end of said body and the lower end of said nipple, a tubing slip whose upper and lower ends are tapered to conform to the taper of and to fit within said 90 respective seats, an internal annular seat in said nipple, annular packing on said last-mentioned seat, a gland on said packing, a flange nut threaded onto the nipple and in engagement with said gland.

In testimony whereof I have signed my name to this specification.

GRANVILLE A. HUMASON.
